CLAIM

The ornamental design for an earpiece, substantially as shown and described.

DESCRIPTION

FIG. 1 is a perspective view of an earpiece as seen from the back, top and left side;

FIG. 2 is a front view thereof;

FIG. 3 is a left side view thereof;

FIG. 4 is a back view thereof;

FIG. 5 is a right side view thereof;

FIG. 6 is a top view thereof; and,

FIG. 7 is a bottom view thereof.

The dotted line portions of the drawings represent environmental structure only and do not form part of the claimed design.
